UNITED STATES PATENT OFFICE

WALTER P. BEAVER, OF STATESVILLE, NORTH CAROLINA

DIGGING DEVICE

Application filed November 22, 1929. Serial No. 409,143.

This invention relates to a device for digging holes, the general object of the invention being to provide a vertically movable cylinder having an auger at its lower end and teeth around the periphery of its lower end, with means for rotating the cylinder so that the cylinder will dig a hole in the ground, with an elevator in the cylinder for raising the dirt from the lower end thereof to a point above its upper end.

Another object of the invention is to provide supporting means for the upper end of the cylinder and a supporting frame on which such means are vertically movable, with motor driven means for rotating the cylinder and for moving it upwardly and hand operated means for lowering the cylinder.

Another object of the invention is to provide a support for the motor and the supporting frame, with means for adjusting the supporting frame and the motor supporting means when the invention is placed on a truck or platform which is not level.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is an elevation with parts in section, showing the apparatus arranged on a truck.

Figure 2 is an elevation with parts in section, looking toward the cylinder.

Figure 3 is a top plan view of parts of the apparatus.

Figure 4 is a section on line 4—4 of Figure 2.

Figure 5 is a section on line 5—5 of Figure 1.

Figure 6 is a section taken through the clutch.

In these drawings, the numerals 1 indicate a pair of circular bearing members supported

by the legs 2 which may be placed on a truck, such as A, shown in Figure 1, so that the apparatus can be transported from place to place and remain on the truck when in use. A circular member 3 is rotatably arranged in each bearing member and has recesses 4 in its sides. A pair of beams 5 pass through the recesses of the two members 3 and are bolted thereto so that the beams are supported for rocking movement by the legs and the bearing members. The beams support a motor M and a vertically arranged channel beam 6 is pivoted intermediate its ends to the outer ends of the beams 5, as shown at 7. A cable 8 has its ends connected with the projecting pieces 9 projecting from the outer sides of the beams 5 and this cable is looped around a pulley 10 journaled in the upper part of the beam 6 and provided with a handle 11 whereby the pulley can be turned to cause the cable to rock the frame, composed of the beams 5 and their associated parts, in the bearing members 1, thus providing means for enabling the parts to be placed in a level position if the truck is not level. A pulley 12 is also rotatably connected with one of the beams 5 and may be rotated by a handle 13 and a cable 14 passes around this pulley and has its ends connected to the upper and lower portions of the beam 6, so that this beam can be placed in a vertical position if the truck is not level. A plumb bob 15 is connected with the beam 6 for facilitating the leveling of the parts.

A vertically arranged I beam 16 has its ends fastened to the beam 6 in spaced relation thereto by the members 17 and that edge of the beam 16, nearest the beam 6, carries a rack bar 18.

The cylinder 19 has a yoke 20 fastened to its upper end and a shaft 21 has its lower end fastened to the upper end of the yoke, this shaft passing through a square part 22 which has a yoke 23 at its upper end and a spider 24 at its lower end, this spider carrying a stationary beveled gear 25. A pair of arms 26 have their outer ends connected with the part 22 and these arms 26 have their other ends embracing the beam 16, a shaft 27 being journaled in said other ends of the arms

26 and passing through the space between the beams 6 and 16. This shaft carries a toothed wheel 28 which meshes with the teeth of the rack and has a handle 29 at one end thereof 5 and a sprocket 30 at its other end. A brace 31 is connected with the outer face of each of the arms 22 and carries the rollers 32 which engage the front and rear edges of the beams 16 so that the arms 26 are slidably supported 10 on the beam 16 and said arms, with the parts associated therewith, can be adjusted vertically by turning the shaft 27, which causes the toothed wheel 28 to run over the rack.

A shaft 33 is journaled in the yoke 23 and 15 this shaft is connected with the shaft 21 by the beveled gears 34 so that when the shaft is rotated, the cylinder will also be rotated. A sprocket 35 is connected with one end of the shaft 33 and a chain 36 passes over this 20 sprocket and over a sprocket 37 on a shaft 38 which also carries the sprocket 39 over which the chain 40 passes, this chain also passing over a sprocket 41 on the shaft of a motor M. A bar 42 having a fork at each 25 end thereof is pivoted at its lower end to the motor shaft and the upper end is pivoted to the shaft 38. A similar bar 43 is pivoted to the shaft 38 and to the shaft 33, so that said shaft 33 is driven from the motor and the 30 driving parts will follow the vertical movement of the supporting means for the cylinder and shaft.

A sprocket 44 is adapted to be connected to the shaft 33 by a clutch 45 and a chain 46 35 passes over this sprocket 44 and the sprocket 30 on the shaft 27 so that when the clutch is in operative position, the shaft 27 will be driven from the motor, whereby the cylinder and its associated parts will be raised by 40 the motor through the engagement of the toothed wheel 28 with the rack. When the cylinder is to be lowered, however, the clutch is moved to inoperative position and the shaft 27 turned by hand. Of course, the cylinder 45 can be raised by hand, if necessary. Guiding means 47 are connected with the lower end of the beam 16 and have portions encircling the lower end of the cylinder for guiding the same in its vertical and rotary 50 movement.

An auger 48 is connected to the lower end of the cylinder by the yoke 49 and teeth 50 are connected with the lower periphery of the cylinder so that as the cylinder is rotated, the auger and teeth will dig into the dirt and loosen the same and thus the loosened dirt will enter the lower end of the cylinder.

A shaft 51 is journaled in the lower end of the cylinder and a shaft 52 is journaled 60 in the yoke 20. These shafts carry sprockets 53 over which passes a chain 54 to which the buckets 55 are connected. The shaft 52 has a beveled gear 56 attached to one end thereof which meshes with the stationary gear 25 so 65 that said shaft 52 and the elevator will be

operated as the cylinder rotates. An idle gear 57 is loosely arranged on the opposite end of the shaft 52 and meshes with the gear 25.

Thus it will be seen that when the cylinder 70 is rotated, the auger and the teeth at the lower end thereof will dig the dirt and loosen the same and this loosened dirt will enter the bottom of the cylinder where it is picked up by the buckets which convey it to the top 75 of the cylinder. Any suitable means may be provided for receiving the dirt from the buckets. The driving means are such that they will follow the movement of the cylinder without interfering with its vertical 80 movement and when it is desired to lift the cylinder, this can be done by moving the clutch into operative position so that the cylinder is raised by power means. I prefer to lower it by hand so that no damage will be 85 done the parts by suddenly striking the bottom of the hole. It will also be seen that the parts can be placed in a level position if the truck is not sitting level.

It is thought from the foregoing description that the advantages and novel features of the invention will be readily apparent.

It is to be understood that changes may be made in the construction and in the combination and arrangement of the several parts, 90 provided that such changes fall within the scope of the appended claims.

What I claim is:—

1. A digging apparatus of the class described comprising a cylinder having digging means at its lower end, a yoke connected with the upper end of the cylinder, a shaft connected with the yoke, supporting means in which the shaft is journaled, a vertically arranged frame slidably engaged by the supporting means, a rack carried by said frame, a shaft in the supporting means, a toothed wheel thereon engaging the rack, a second shaft journaled in the supporting means and geared to the shaft which is attached to the cylinder, power means for driving the second shaft, means, including clutch means, for connecting the second shaft with the toothed wheel carrying shaft and a handle on the toothed wheel carrying shaft. 100 105 110 115

2. A digging apparatus of the class described comprising a cylinder having digging means at its lower end, a yoke connected with the upper end of the cylinder, a shaft connected with the yoke, supporting means in which the shaft is journaled, a vertically arranged frame slidably engaged by the supporting means, a rack carried by said frame, a shaft in the supporting means, a toothed wheel thereon engaging the rack, a second shaft journaled in the supporting means and geared to the shaft which is attached to the cylinder, power means for driving the second shaft, means, including clutch means, for connecting the second shaft with 120 125 130 135

the toothed wheel carrying shaft, a handle
on the toothed wheel carrying shaft, a con-
veyor vertically arranged in the cylinder
and means for operating the same from the
power means.

5 In testimony whereof I affix my signature.

WALTER P. BEAVER.
